(57) **CLAIM**

I claim the ornamental design for a bottle top, as shown and described.

DESCRIPTION

FIG. 1 is a top plan view of a bottle top according to a first embodiment of my new design;

FIG. 2 is a bottom plan view thereof;

FIG. 3 is a top perspective view thereof;

FIG. 4 is a bottom perspective view thereof;

FIG. 5 is a left side elevation view thereof, the right side elevation view being a mirror image of the left side elevation view;

FIG. 6 is a top plan view of a bottle top according to a second embodiment of my new design;

FIG. 7 is a bottom plan view thereof;

FIG. 8 is a top perspective view thereof;

(Continued)

FIG. 9 is a bottom perspective view thereof; and, FIG. 10 is a left side elevation view thereof, the right side elevation view being a mirror image of the left side elevation view.

1 Claim, 10 Drawing Sheets
